CLAIM

I claim the ornamental design for a hold down cap for a ladder leveler foot, as shown and described.

DESCRIPTION

FIG. 1 is an exploded view of the hold down cap for a ladder leveler foot; the broken lines are for illustrative purposes only and form no part of the claimed design;

FIG. 2 is a top plan view thereof in assembled position;

FIG. 3 is a side elevation view thereof the opposite side is identical thereto;

FIG. 4 is a top plan view of the bottom part of the hold down cap for a ladder leveler foot;

FIG. 5 is a side elevation view thereof, the opposite side being identical thereto;

FIG. 6 is a bottom view thereof;

FIG. 7 is a top plan view of the top part of the hold down cap for a ladder leveler foot;

FIG. 8 is a side elevation view thereof, the opposite side being identical thereto; and,

FIG. 9 is a bottom plan view thereof.
